Primary Examiner — Ralf Seifert(74) *Attorney, Agent, or Firm* — Renner Kenner Greive
Bobak Taylor & Weber(57) **CLAIM**

The ornamental design for a balloon inflation device, as shown and described.

DESCRIPTION

FIG. 1 is a perspective view of the balloon inflation device of this invention;
 FIG. 2 is a front elevational view thereof;
 FIG. 3 is a left-side elevational view thereof;
 FIG. 4 is a right-side elevational view thereof;
 FIG. 5 is a top plan elevational view thereof; and,
 FIG. 6 is a rear elevational view thereof, the bottom view not forming part of the claimed design and thus not shown.
 In the drawings, the ghost-line portions do not form a part of the design sought to be patented.
